(57) **CLAIM**

The ornamental design for a cup for beverages or food, as shown.

DESCRIPTION

FIG. 1 is a front elevational view of a cup for beverages or food, showing my new design;
FIG. 2 is a rear elevational view thereof;
FIG. 3 is a top plan view thereof;
FIG. 4 is a bottom plan view thereof;
FIG. 5 is a left side elevational view thereof;
FIG. 6 is a right side elevational view thereof;
FIG. 7 is a top perspective view thereof, wherein the separable spoon is in an alternate position; and,
FIG. 8 is a cross-sectional view thereof, taken along the line VIII—VIII of FIG. 3.
